NICOLA LENGERSDORFF, OF DRESDEN, GERMANY.

KILN AND LIKE STRUCTURE, AND HEAT TREATMENT.

Application filed February 9, 1924. Serial No. 691,688.

To all whom it may concern:

Be it known that I, NICOLA LENGERSDORFF, a citizen of Germany, and resident of Dresden, Germany, have invented certain new and useful Improvements in Kilns and like Structures, and Heat Treatments, of which the following is a specification.

My invention relates to kilns and furnaces, particularly of the type in which the structure comprises a longitudinal passage or tunnel through which the material or the goods to be treated are caused to travel.

The specific embodiment of my invention illustrated by the accompanying drawings has been designed for the treatment of materials or goods which contain more or less moisture which it is desired to drive out; for instance, the kiln illustrated may be used for the burning of porcelain, bricks of various kinds, tiles and other articles of clay or the like, as well as for the burning of lime. It will be understood, however, that the invention is of broader application than the specific embodiment and uses expressly disclosed herein.

The object of my invention is to obtain superior results both with respect to the effect of the treatment on the ware or material and as regards economy in the amount of fuel required. This I obtain by novel arrangements for regulating the supply of the heating agent and for utilizing the heat taken up by the goods or material, as well as by other novel features which will be pointed out hereinafter.

Reference is to be had to the accompanying drawings, in which Figs. 1, 1^a and 1^b are fragmentary longitudinal central sections of the kiln, each of these views being a continuation of the others, Fig. 1 being the left hand end, Fig. 1^a the middle portion, and Fig. 1^b the right hand end; Fig. 1^c is an elevation partly in section showing a gas producer, separator, purifier and cooler; Figs. 2, 2^a and 2^b are corresponding fragmentary horizontal sections, substantially on lines 2—2, 2^a—2^a and 2^b—2^b of Figs. 1, 1^a and 1^b respectively; Fig. 2^c is a plan view of Fig. 1^c with parts in section; Fig. 3 is a vertical cross section on line 3—3 of

Fig. 1; Fig. 3¹, a vertical cross section on line 3'—3' of Fig. 1; Fig. 4 is a section on line 4—4 of Fig. 1^a; Fig. 4¹ is a section on line 4'—4' of Fig. 1^a; Fig. 5 is a section on line 5—5 of Fig. 1^b; Fig. 5¹ is a section on line 5'—5' of Fig. 1^b.

At the right-hand end (Figs. 1^b and 2^b) of the apparatus illustrated, I have indicated at 1 a gas producer of any well-known or approved type, constructed to deliver gas under pressure to a separator 2 for the removal of dust, from which the gas passes through a temperature regulator 3 to a disintegrator or purifier 4 of any suitable character adapted to remove from the gas, any dust remaining therein, as well as the tar contained in the gas. At 5 I have indicated a cooler receiving the gas from the purifier 4, and at 6 a vaporizer for obtaining the vapor-and-air mixture required for the producer. 7 designates a pressure regulator contained in the pipe 8 through which the purified gas, under pressure, is conveyed from the cooler 5 to the kiln or furnace proper. The pipe 8, which is a single conduit at first, has two branches where it runs within or along the sides of a kiln proper. At that end of the kiln which is nearest the gas producer, the two branches of the pipe 8 are located within ducts or channels 8^a located in the roof of the kiln, at the sides thereof, and thus the gas flowing through these portions of the pipe 8 is heated, partly by radiation of heat from the interior of the kiln, and partly by the passage of hot air through the channels 8^a, such air being supplied from a recuperator, as will be explained below. At the main heating zone of the kiln, the two branches of the pipe 8 are located exteriorly of the kiln proper (see Figs. 1^a and 4) and provided with a plurality of feed tubes 9 having individual independent regulating devices 9^a and leading to the respective burners 10 projecting their flames transversely into the longitudinal passage or tunnel 11 of the kiln. The burner orifices may be arranged in two tiers, and they are disposed exactly opposite each other on the two sides of the passage 11 so that the two flame jets

directed toward each other from the two registering orifices or nozzles of the same pair will meet with their points at the center of the kiln, the gas pressure being adjusted (by the regulators 7 and 9^a) to project the flames to this distance, and the ware or material under treatment being stacked or arranged with transverse channels or spaces to allow the flames to be thus projected.

The ware or material is placed on trucks 12 traveling on a longitudinal track. Underneath this track is located a passageway 13 for making inspections and repairs, access to such passageway being had through transverse adits 13^a. The main heating or burning zone into which the flame jets are discharged, is designated by 14, while 15 indicates the preliminary heating zone 20 through which the goods (traveling from left to right according to the showing in the drawings) pass before they reach the main heating zone 14.

From the preliminary heating zone 15 smoke and moist air are carried away through outlets 16^a and 16^b located at different points of the length of said zone. These outlets are provided with independent dampers or other regulating devices so that the draft may be adjusted for the outlets 16^a independently of the outlets 16^b, and vice versa. To this preliminary heating zone, hot air (from a source referred to below) is delivered through individually regulatable channels 17. The outlets 16^a and 16^b are connected by ducts 18 (controlled by suitable individual regulating devices) with the suction inlet of a fan or blower 19 which forces the smoke etc. into the stack 20.

At the end of the kiln nearest to the gas producer 1 is located the cooling zone 21, and at the junction of this zone with the main heating zone the passage 11 is formed with lateral enlargements 22, in which the hot air within the passage 11 may expand so that it may travel more readily to the burners through the path to be described presently. From the lower portion of the enlargements 22 longitudinal channels 23 conduct the hot air to branch ducts 23^a, provided with individual regulating devices 23^b and delivering heated air, in adjustable amounts, to the individual burner nozzles (see the left-hand portion of Fig. 4).

Another supply of air is taken in at inlets 24^a and passes through heaters or recuperators 24 located in the side walls of the kiln (to the right of the enlargements 22, Figs. 1^a and 2^a) to a channel consisting of sections 25^a, 25, 25^b located in the roof of the kiln and connected with the air delivery channels 17. Suitable regulating devices are provided in this connection also, as mentioned above.

Adjacent to the cooling zone 21 of the kiln radiators 26 are shown, located in the side walls, so as to cool the inside of the kiln and at the same time heat the water or air contained in the radiators, such water or air being used for any purpose desired, for instance the hot air thus obtained may be used for drying.

The trucks 12 may be moved along the passage 11 by any well-known or approved pushing or pulling device, indicated diagrammatically at 27. The kiln is also provided with suitable doors or flaps at the ends of the longitudinal passage 11.

It will be understood that the structure of the kiln proper is absolutely symmetrical with reference to the longitudinal central plane in which Figs. 1, 1^a and 1^b are taken, that is to say, the arrangement of the kiln parts to the left of such plane is exactly the same as on the right of said central longitudinal plane.

The material or goods enter the kiln passage 11 at one end and travel therethrough gradually to the other end, at which they emerge from the kiln proper.

One of the important characteristic features of my invention is the use of purified gas under pressure, the supply of such gas being regulatable independently for each individual burner, and the air for supporting combustion being fed to each burner in a heated condition, by the suction which the stream of gas exerts, and such air supply is preferably also regulatable independently for each individual burner. The drawings indicate regulating devices at various points of the apparatus, enabling the operation to be controlled very accurately. The burners 10 are preferably annular burners made of refractory material (fireclay or the like).

The utilization of heat is very thorough in my kiln, which is evidenced by the relatively low temperature of the gases leaving the kiln at 18. When the kiln is employed for burning porcelain, I find that the temperature of the gases drawn off at 18 will average about from 100 to 120° centigrade. More particularly, the losses due to incomplete combustion are very slight.

It will be noted that I recover a considerable portion of the heat supplied to the main heating zone, and utilize the heat thus recovered, for the preliminary heating of the material or goods on the way to such main heating zone. Thus, if the kiln is used for burning porcelain, the heat applied in the preliminary heating zone will serve to dry the clay and to convert it into porcelain. Tests show that in a kiln constructed according to my invention, about 12% of the total heat effect is required for this preliminary heating. The latter operation is performed by means of heat abstracted from the cooling zone of the kiln. I have found

- that about 50% of the heat stored in the finished material or goods as the result of the main heating operation will be sufficient for heating the air which is fed to the burners for supporting combustion. The remainder of the heat present in the cooling zone is utilized for the preliminary heating operation; this may be done in the indirect manner described above, with the aid of a recuperator such as 24, or, instead of this, a portion of the hot air in the passageway 11, may be withdrawn through a by-pass and diverted to the channels 17, in substantially the same manner that hot air is led to the ducts 23^a.
- It will further be noted that the channels 17 for the admission of hot air are located between the two sets of outlets 16^a and 16^b through which the moisture and gases are withdrawn. By this arrangement I am enabled to remove moisture from the goods or material under treatment, without any injury to said goods or material, and this is of special importance when the material contains a relatively large amount of moisture.
- The success of this drying operation is assisted materially by the attendants being able to adjust individually, not only the sets of outlets 16^a and 16^b, but the air inlets 17 as well.
- By the arrangements shown and described, I am enabled to utilize the heat most efficiently by adjusting the supply of air and gas in such a manner as to secure, at each point of the passageway 11, the degree of heat that will secure the best results at such point. The amount of pressure for the proper operation of the burners, is relatively small. Each burner discharges the gas in the form of an annular jet, which will entrain an annular stream of hot air. It will be noted that the gas and the air for supporting combustion are well mixed with each other before they enter the passage 11, and in this manner I obtain much better results than if the mixture of air and gas took place in such passage, as it does in some earlier constructions.
- The heating in zones, which is a characteristic feature of my invention, is obtained in a manner which does not interfere with the proper flow of the hot air in the passage 11; this independence of said two features is due chiefly to the provision of the lateral enlargements 22, which release the hot air so that, by the suction exerted by the individual gas jets, such air may be brought to the several burners. When gas and air are caused to mix and combine while they are both hot and in the shape of annular jets or streams, the velocity with which the resulting mixture flows is greatly increased. Thus, for instance, if the gas pressure is equal to that of a column of water of a height of from 6 to 7 millimeters, and if the interior width of the kiln is six feet, the points of the two flame jets discharged in opposite directions from transversely registering burner nozzles will meet in the longitudinal central plane of the passage 11, each flame (measuring from the tip of the respective burner 10) having a length of about five feet. It will be noted that the burner tips are at a relatively considerable distance (about two feet) from the passage 11, so that gas and air will have ample opportunity for mixing before they reach the passage 11, thus insuring a thorough mixture; and the fact that these two constituents are hot at the time of their mixture, enables me to carry out the heating operation in readily regulatable zones having the various desired effects on the material under treatment, such as a reducing effect, a neutral effect or an oxidizing effect.
- The charge or stack of goods or material carried by the trucks is preferably arranged loosely, so as to present slits both horizontally and vertically, especially at the lower portion of the kiln and between neighboring trucks.
- In a kiln constructed according to my invention and used for burning porcelain at a temperature of 1400 degrees centigrade, the temperature of the air withdrawn from the cooling zone, for use at the burners, was found to be 1000 degrees centigrade. This indicates a very large recovery of heat and explains the relatively small percentage of the heat required for the preliminary heating (drying and porcelain-forming) operation.
- The particular zone heating system described also enables me to withdraw the waste gases, in a regulatable manner, at those points of the preliminary heating zone at which the respective gas portions have accomplished the desired result. The possibility of thus regulating the withdrawal of the waste gases is of considerable importance in view of the fact that their saturation point (that is, the point at which they are unable to take up any further amount of moisture) is reached at different points of the length of the kiln, depending on the character of the material under treatment, and particularly on the degree of moisture contained in such material. It is for this purpose that I have provided a plurality of independently regulatable outlets (such as 16^a and 16^b) at different points of the length of the preliminary heating zone.
- Other advantages of the zone heating system described herein are as follows: It enables hot air for supporting combustion to be taken from a portion of the kiln where the material under treatment has been burned or otherwise treated to the desired point but is still very hot, such hot air being taken off through the enlargements 22, as described. I may also heat air by radiation

(as in connection with the recuperator 24) and bring such heated air, as described, to the preliminary heating zone in order to dry or preheat the goods or material under treatment. In the cooling zone air or water contained in the radiators 26 may be heated and then conducted to a place of use, for instance for drying operations.

Instead of purified gas, I may employ oil 10 (under pressure) as the fuel supplied to the burners.

When using the zone heating system described, the burners 10 are adjusted from the outside of the kiln until the points of the 15 opposing flame jets meet at the center of the kiln passage.

The heating arrangement may be extended or shifted horizontally as well as vertically.

With this zone system of heating, therefore, 20 the heating devices are quite independent of the open longitudinal passage 11, since the hot air for supporting combustion is supplied to each of the burners in individually regulatable amounts. While the heating 25 system is thus independent, it is desirable, in order to obtain the best results, to maintain a practically uniform composition of the heating gas or other fuel, and also to regulate the draft through the kiln and keep 30 it constant by means of a blower or other suitable device. In this case, the kiln would operate under the following especially favorable 35 conditions: First, fuel (and particularly heating gas) of uniform composition, temperature and pressure; second, constant draft; and third, a temperature uniform within each of the several zones of the kiln.

Various modifications may be made without departing from the nature of my invention 40 as set forth in the appended claims.

I claim as my invention:

1. The process of treating goods or material, which consists in heating them by 45 flames, then carrying them away from such flames, into contact with air to be heated by such hot material, and then carrying such heated air, in amounts, to the several flames, to support combustion, the amount of heated air delivered to each flame being independently 50 regulated with respect to the flame which it serves.

2. The process of treating goods or material, which consists in passing them between and in direct contact with flame jets 55 directed toward each other transversely of the path of said material and of such length as to cause the points of opposed jets to meet at the longitudinal central plane of said path.

3. The process of treating goods or material, which consists in passing them first through a preliminary heating zone, then through a main heating zone, and finally 60 through a cooling zone, utilizing the heat prevailing in said cooling zone, for heating

air, leading the air thus heated to the preliminary heating zone, and withdrawing gases from said preliminary heating zones at points both in advance and in the rear of the region at which heated air is admitted 70 to said preliminary heating zone.

4. A kiln or like structure having a longitudinal passage, burners adjacent to one portion of said passage, connections for taking heated air from another portion of said passage and leading such air to said burners, and air-regulating devices associated with the several burners for independently regulating the air supply to each of said burners. 75

5. A kiln or like structure having a longitudinal passage, burners adjacent to one portion of said passage, connections for taking heated air from another portion of said passage and leading such air to said burners, individual fuel-regulating devices associated 80 with the several burners, and air-regulating devices associated with the several burners for independently regulating the air supply to each of said burners. 85

6. A kiln or like structure having a longitudinal passage with lateral enlargements constituting expansion chambers for heated air, burners located adjacent to a portion of said passage, to one side of said enlargements, and connections for leading the expanded heated air from said enlargements 90 to the burners. 95

7. A kiln or like structure having a longitudinal passage, heating means located adjacent to one portion of said passage, air-heating means located adjacent to a portion of the passage to one side of the first-named portion, air-inlets located at a portion of said passage on the opposite side of the said first-named portion, and connections for 100 leading hot air from said air-heating means to said air-inlets. 105

8. A kiln or like structure having a longitudinal passage with hot-air inlets at one portion thereof, waste gas outlets both in 110 advance and in the rear of said inlets, and heating means adjacent to a portion of the passage in advance of said inlets and outlets.

9. A kiln or like structure having a longitudinal passage with hot-air inlets at one 115 portion thereof, waste gas outlets both in advance and in the rear of said inlets, independent regulating means for the outlets located in advance of the inlets and for those located in the rear thereof, and heating 120 means adjacent to a portion of the passage in advance of said inlets and outlets.

10. A kiln or like structure having a longitudinal passage, means, located adjacent to a portion of said passage, for producing a relatively moderate heat therein, means located adjacent to a portion of said passage in advance of the first-named portion, for producing a higher degree of heat, and heat-absorbing device located adjacent to a por- 125 130

tion of the passage in advance of the second-named portion.

11. A device of the character described, comprising a gas producer, gas-purifying means connected with the outlet of said producer, a device for regulating the pressure of the purified gas, and a kiln or like structure pro-

vided with burners receiving purified gas under regulated pressure, from said producer and purifier.

In testimony whereof I have signed this specification. 10

NICOLA LENGERSDORFF.
